UNITED STATES PATENT OFFICE

2,380,548

ZINC CONDENSER

Augustin Le-n Jean Queneau, Morristown, N. J.
assignor to United States Steel Corporation of
Delaware, a corporation of Delaware

Application April 16, 1942, Serial No. 439,266

3 Claims. (Cl. 266—17)

In zinc metallurgy, many forms of condensers for evolved zinc vapors produced by the reduction of zinc ores have been evolved for the purpose of condensing the zinc vapors to liquid zinc which can be cast into slabs of metallic zinc. The fundamental design of the condensers of all types, however, is intended to effect the condensation of the zinc with the minimum production of blue powder.

The construction of the condenser employed is related definitely to the reduction process, and the efficiency of each condenser is predicated importantly upon the composition of the gas stream entering the condenser, and the efficiency of contact thereof with condensing surfaces.

The reduction of zinc ores in vertical retorts and shaft furnaces is of increasing importance. In all of these operations, the heat required for the reduction is supplied from the outside of the retort either by conduction, convection, or radiation, or by electrical heat liberated in situ within the charge itself.

The process of the reduction of the zinc vapors in accordance with the present invention is based upon the reduction of the zinc oxide in a shaft furnace heated by direct internal combustion of carbon produced by pure anhydrous oxygen, giving rise to a widely different set of conditions from those existing in any other type of zinc reduction furnace. The present improved reduction process effects the reduction of zinciferous materials in a shaft furnace internally heated by the combustion of carbon (metallurgical coke) in a blast at appropriate pressure (for example, 10 to 12 pounds) of pure anhydrous oxygen.

The various types of condensers proposed or in use for the condensation of the zinc vapor from the streams of zinc vapors and gases, carbon monoxide and occasionally hydrogen in small amounts, issuing from large industrial furnaces externally heated, as in the case of vertical zinc retorts, or internally heated by electrical resistance of the furnace charge or by an electric arc, as in the case of electrothermic zinc processes, are not applicable to the special problem of the condensation of zinc vapor from the streams of zinc vapor and carbon monoxide issuing from a shaft furnace of the type herein described, heated internally by the combustion of carbon in a blast of oxygen, for while the same carbon monoxide and zinc vapor are present, they are present, in this specific instance, in widely different volumes from the vapor-gas stream from the classic Belgian retort process, or from the vapor-gas streams from the continuous vertical retort proc-

ess or of the shaft furnaces utilizing electrothermic reduction.

In all of these instances the major chemical reactions are the same, namely,

secondary reactions here being neglected, such as the reduction of iron and/or manganese oxides present in minor quantities in the zinc ore of the furnace burden. In the foregoing procedures, for one pound of reduced zinc vapor, there are 5.48 cubic feet of carbon monoxide, volume taken at standard conditions of temperature and pressure.

However, in the case of the present process in which all of the heat requirements are produced within the reduction shaft furnace by the combustion of carbon in pure oxygen, the ratio is as follows: For one pound of zinc vapor there are 26.32 cubic feet of carbon monoxide. Thus, there is an increase for the same pound of zinc, from 5.48 cubic feet to 26.32 cubic feet, or an increase of substantially 1 to 5.

This enormous increase in the volume of uncondensable gas, accompanying the condensable zinc vapor, gives rise to conditions in the zinc condenser which cannot be handled by the heretofore proposed condenser constructions, either those of the surface condenser type, or the condensers wherein a large body of molten zinc is "sloshed" back and forth by the high suction created by a vacuum pump.

It is found in practice that the use of pure oxygen in a shaft furnace for zinc produces operating efficiency highly above those obtainable by the usual operations. However, in view of the enormous increase in the volume of uncondensable gas accompanying the condensable zinc vapors there has been necessitated the construction of a new type of condenser in which the mixture of zinc vapor and carbon monoxide is not passed into a body of zinc in liquid form, but is made to pass over a body of liquid zinc, as is done in the Belgian zinc condenser.

But in the present improved construction the vapor-gas stream is divided into a number of smaller streams by windows cut into walls extending transversely to the longitudinal axis of the condenser. Owing to the velocity of these gas streams, the surface of the molten zinc is depressed and pushed toward the exit end of the condenser. Also, the violent and turbulent passage of the gas streams tears bodily from the molten zinc, drops and splashes which are projected against the forward partitions, and upper

free surfaces of the condenser. The zinc so projected drops back into the main body and efficiently scrubs the passing stream of vapor and gas. These steps are repeated at each condenser wall.

The oxygen blast for effecting the reduction of the zinc ores in the shaft furnace is blown through the tuyères of the furnace at a pressure sufficient to overcome the resistance offered to its passage by the burden within the shaft furnace, as well as the resistance of the condenser itself, and of the scrubbing system through which the carbon monoxide with any small proportions of uncondensed zinc vapor is made to pass before reaching the gas holder for the purified carbon monoxide. This initial oxygen pressure supplies the energy necessary for the operation of the condenser.

Such operating conditions are not present either in the procedures involving the use of a vertical retort, a "flash reduction" column, nor in shaft furnaces employed for electrothermic zinc reduction operations. In the present process new conditions are set up which require new means for handling.

In all prior procedures as noted above, the pressure of the zinc vapor and carbon monoxide, liberated by the reducing Reactions 1 and 2 noted above herein, is that of the furnace atmosphere that is slightly above atmospheric pressure. It is insufficient to force the passage of the gas and zinc vapor through any depth of molten zinc. Therefore, in some operations a vacuum pump is employed to draw the gas and zinc vapor through a collected body of molten zinc, for effecting condensation. In other operations using the so-called vertical retort in order to increase the volume of the retort reduction gaseous products, there is introduced by means of a positive blower a metered amount of air at the base of the vertical retort at a point above the water seal. This air coming in contact with the carbon of the hot briquettes forms additional carbon monoxide:

which helps to sweep upwards to the condenser the reduction gases, zinc vapor and carbon monoxide. Additionally, there is a certain amount of steam generated by the exiting spent hot briquettes falling into the water of the water seal. This steam rises through the vertical retort and in contact with the hot carbon of the briquettes forms additional carbon monoxide and hydrogen:

This additional gas volume assists in the evacuation of the gaseous products of the zinc reduction. But there is nothing which approaches the positive ten to twelve pounds pressure of the reduction gases issuing from the oxygen fed zinc shaft furnace.

Consequently, the present improved condenser construction has been devised to accommodate the greatly increased volumes of gases and the effects of the positive pressures employed in the present improved process.

The condenser of the present invention is illustrated in the accompanying drawings, in which:

Fig. 1 is a longitudinal sectional elevation through a condenser constructed in accordance with the improvements of the present invention, the view being taken on the longitudinal center line of the condenser;

Fig. 2 is a transverse sectional elevation through the condenser of Fig. 1, the view being taken on

the line II-II of Fig. 1, looking in the direction of the arrows; and,

Fig. 3 is a sectional plan view of a modified form of condenser.

Referring more particularly to the drawings and to Figs. 1 and 2, the condenser construction illustrated therein comprises a metal shell 5 such as sheet steel or the like, which is lined with a suitable number of courses of refractory brick 7, which may be made of silicon carbide or carbon.

Extending transversely across the interior of the condenser is a plurality of transverse partitions 9, each of which is provided with a plurality of rather large openings or windows 11, the level of which above the condenser floor is raised from the inlet end 13 of the condenser to the outlet end 15 so as to maintain a uniform depth of molten zinc to be depressed and agitated by the flowing stream of vapor and gas throughout its length. The outlet end 15 is provided with a suitable tap hole 14, for providing drainage for the condenser at the end of a run. Such a tap hole is provided conventionally in all types of zinc condensers.

The design of these windows 11 in relation to the inlet pressure of the gas stream is such as to allow a depression of from approximately six to approximately eight inches in the bath of molten zinc of the condenser.

Each of the transverse partitions 9 has a small port 17 which allows restricted communication between all sections of the pool 20 of molten zinc.

The condenser communicates with a holding furnace 19 for the zinc in a manner which now will be described. This communication is effected by providing graphite cylinders 21 and 23, which may be made from nine-inch square graphite electrodes, the cylinder 21 being drilled with a hole 25 extending partly therethrough, and cylinder 23 having a hole 27 drilled all the way therethrough, so that when the cylinder 23 is assembled the hole 27 communicates with hole 25, forming a passage through which zinc may flow from the condenser into the furnace 19.

The pipe 23 is covered by a layer of refractory 29, which is enclosed in a metal sheath 31. The furnace 19 is provided with a tap hole 33, shown as closed by a plug 35, opening of the tap hole 33 allowing zinc to flow out of the furnace 19 over a lip 37 into a suitable large ladle from which the molten zinc is poured into the usual molds in which the zinc solidifies into slabs.

As will be seen from Figs. 1 and 2, a high velocity zinc vapor-gas stream enters the condenser through intake 13, which leads from the reduction zinc furnace (not shown) which operates similarly to a blast furnace except that combustion is supported by pure oxygen introduced through the tuyères of the furnace under sufficient pressure to maintain a super-atmospheric pressure of from about ten to about twelve pounds in the furnace.

After passage through suitable instrumentalities for removing entrained solids from the vapor-gas stream, this latter passes under high velocities induced by the said pressure into the condenser, which condenses zinc from the stream to form the pool 20 of molten zinc in the condenser.

The continued entry of the high velocity gas stream, which stream is subdivided by the windows 11 into smaller streams, likewise of high velocity, results in the pool so being swept by the incoming high velocity vapor-gas streams. Owing to the high velocity of these vapor-gas

streams, and in view of the ports 17 affording free communication between the various sections of the pool, the surface of the pool 20 is depressed and pushed towards the exit end 15 of the condenser as shown in the drawings. Also, the violent and turbulent passage of the vapor-gas streams tears bodily from the pool 20, drops and splashes of the molten zinc which are projected against the forward partitions, and upper free surface of the condenser. The zinc so projected drops back into the main molten zinc body and efficiently scrubs the passing streams of zinc vapor and gas, condensing the zinc therefrom. These actions are repeated at each condenser division walls 8.

The residual carbon monoxide with a small percentage of uncondensed zinc passes out from the condenser through a stack 38 to suitable scrubbing instrumentalities of well-known type, such as a wet cyclone and scrubbing tower where it meets in its upward travel a washing stream of water. The resulting clean carbon monoxide may be passed to a suitable gas holder.

A modified form of condenser is illustrated in Fig. 3, which operates in a manner similar to that described above.

In the form of condenser shown in Fig. 3, instead of a long cylindrical condenser of fifteen or more feet in length of the type shown in Figs. 1 and 2, the requisite length of travel of the vapor-gas stream may be attained by the use of two or more short chambers suitably communicating so that the vapor-gas stream will be doubled back upon itself a suitable plurality of times. In Fig. 3 two chambers are shown, which communicate at their far ends.

In Fig. 3 the condenser structure 41 is divided longitudinally by a dividing wall 81, which may be built up of silicon carbide bricks or carbon, thereby forming two condenser chambers 43, 45 which communicate through windows 47 located remotely from the vapor-gas intake 49 which opens into the chamber 43.

The other condenser chamber 45 is shown as communicating with outlet passage 51, corresponding to passage 25, this in turn communicating with a passage 53, similar to passage 27, in graphite pipe 55, corresponding to pipe 23, which leads to a holding furnace for molten zinc, similar to furnace 19 but not shown in Fig. 3.

Therefore, it will be seen that the direction of flow of the vapor-gas stream is reversed as it passes through the condenser system, and the condensing chambers 43, 45, may be increased in number to whatever capacity may be required for a given installation, the arrangement being such that the direction of flow is reversed for each chamber.

Each chamber is divided into sections by transverse partitions 57, which are similar to partitions 8 of the construction of Figs. 1 and 2, and which likewise are provided with windows 59, which are similar to windows 11 and are placed likewise at increasing heights in the direction of gas flow, and are provided also with small ports corresponding to ports 17.

The operation of the condenser of Fig. 3 is similar to the operation of the condenser of Fig. 1, described above, except that the high velocity vapor-gas stream is subjected to centrifugal force in swerving around and through the partitions, the carbon monoxide and the zinc vapor being thrown forcibly into contact with the walls of the condenser. This is due to the fact that the vapor-gas stream entering through intake 49 im-

pings first mainly upon partition 81, which, together with somewhat lessened velocities caused by the stream entering the enlarged chamber 43 produces a vigorous swirling of the stream as it passes through the condenser system, thoroughly wetting all surfaces with droplets of molten zinc, which thus contact the walls and surfaces, wetting them and trickling down to the pool of molten zinc in the bottom of the condenser.

10 The condenser structures herein shown and described operate very efficiently in practice in condensing zinc from high velocity vapor-gas streams entering the condenser in large volumes, from a zinc reduction shaft furnace operating on pure 15 oxygen as the combustion-supporting agent.

Referring to Fig. 3, the carbon monoxide stream carries any small amounts of zinc vapors that have not been condensed, passes from the condenser through off-take 62, and are handled as 20 before.

In both illustrated forms of the condenser, as the level of the zinc pool in the condenser rises through additions of molten condensate derived from the incoming vapor-gas stream, equivalent 25 amounts of molten zinc are forced through the outlets 18, channels 26 and 27 (51, 53) to the pool of the holding furnace.

Suitable clean-out doors with appropriate refractory plugs and covers, not shown, obviously 30 may be provided as desired.

I claim:

1. A condenser for condensing the zinc content of high velocity zinc vapor-gas streams from a blast furnace using pure oxygen as the supporter 35 of combustion of reduction reactions, which comprises in combination, a condenser environment having refractory walls, an inlet for the zinc vapor-gas stream, partition means extending transversely across the condensing environment 40 dividing the environment into sections, bottom ports in each of the partition means providing communication from one of the said sections to adjoining sections, thereby enabling formation of a continuous pool of condensed molten zinc 45 extending throughout the bottom of the condenser environment, and openings in the said partition means for subdividing the incoming zinc vapor-gas stream into a multiplicity of smaller high velocity streams.

2. A condenser for condensing the zinc content of high velocity zinc vapor-gas streams from a blast furnace using pure oxygen as the supporter 50 of combustion for reduction reactions, which comprises in combination, a condenser environment having refractory walls, an inlet for admitting the zinc vapor-gas stream into the condenser environment, partition means extending transversely across the condensing environment 55 dividing the environment into sections, bottom ports in each of the partition means providing communication from one of the said sections to adjoining sections, thereby enabling formation of a continuous pool of condensed molten zinc 60 extending throughout the bottom of the condenser environment, openings in the said partition means for subdividing the incoming zinc vapor-gas stream into a multiplicity of smaller high velocity streams, an outlet for stripped gas, the said openings increasing in height from the inlet towards the outlet, and means for continuously withdrawing condensed zinc from the condenser in conformity with the condensation of zinc from the zinc vapor-gas streams.

3. A condenser for condensing the zinc content of high velocity zinc vapor-gas streams from 70

75

a blast furnace using pure oxygen as the supporter of combustion for reduction reactions, which comprises in combination, a condenser environment comprising a plurality of condensing chambers, a communication between the said chambers so that the zinc vapor-gas streams reverse in direction of flow through the chambers, an inlet for introducing the zinc vapor-gas stream into one of the chambers in a location remote from the said communication, outlet means in 10 another chamber also remote from the communication.

5 cation for removing stripped gas from the condenser, partition means in the chambers dividing the chambers into sections, openings in the said partition means for subdividing the incoming zinc vapor-gas stream into a multiplicity of smaller high velocity streams, the said streams impinging upon condenser walls, and partition means under action of centrifugal force, and means for removing condensed zinc from the condenser.

AUGUSTIN LEON JEAN QUENEAU.
